UNITED STATES PATENT OFFICE.

EERO W. HELIN, OF JAMAICA, NEW YORK, ASSIGNOR OF ONE-HALF TO WILLIAM C. DILLMAN, OF NEW YORK, N. Y.

EXPLOSIVE-ENGINE.

1,050,456.

Specification of Letters Patent.

Patented Jan. 14, 1913.

Application filed February 8, 1912. Serial No. 676,439.

To all whom it may concern:

Be it known that I, EERO W. HELIN, of Jamaica, Queens county, New York, have invented a new and useful Improvement in Explosive-Engines, of which the following is a full, clear, and exact description.

My invention relates to improvements in explosive engines such as gas or internal combustion engines, and the object of my invention is to produce a simple and highly efficient engine which embodies the best principles of both the reciprocating and rotary type of engines. In carrying out this idea, I arrange a plurality of cylinders in a rotary casing which is suitably supported, and provide for reciprocating pistons within the cylinders and transmitting the reciprocating motion of the pistons to a rotary movement of the main casing, and to a shaft connected therewith. In furtherance of this idea, I preferably balance the cylinders, that is arrange them so that they will come on diametrically opposite sides of the axis of the engine at the time of an explosion, so that the explosion will take place simultaneously in two opposed cylinders, thereby reducing the strain or cramping of the apparatus.

By the general arrangement suggested I am enabled to take in the explosive gases at one end of the machine and exhaust them after they have been exploded from another part of the machine, and it will be seen that by having the main casing revolve, and having the intake and exhaust ports connecting with the ports located in stationary parts, I avoid the use of valves, as the rotation of the casing serves to open and cut off the ports, and it is only a matter of properly arranging the registering ports to get the best results and to entirely avoid valves.

A further object of my invention is to arrange the pistons and their crank shafts so that the crank shafts will be geared to a stationary gear or equivalent stationary connection, whereby the rotation of the shafts against the aforesaid stationary connection will impart a rotary movement to the casing in which the crank shafts are mounted.

Reference is to be had to the accompanying drawings forming a part of this specification, in which similar reference characters indicate corresponding parts in all the views.

Figure 1 is a detail longitudinal section of the engine embodying my invention. Fig. 2 is a cross section on the line 2—2 of Fig. 1. Fig. 3 is a cross section on the line 3—3 of Fig. 1. Fig. 4 is a cross section on the line 4—4 of Fig. 1, and Fig. 5 is a longitudinal section on the line 5—5 of Fig. 1, showing in detail the arrangement of one of the cylinders in its crank casing, and the intake port.

The engine can be provided with any suitable frame or support 10, and in this is rigidly mounted so as not to turn, a shaft 11 which is preferably hollow and which forms a partial support for the engine casing, this shaft 11 entering another shaft 12 which is rotatable and which serves to support the second end of the engine. The object of having the shafts hollow is so that the shaft of a magneto can be passed through the hollow shaft 11—12 if desired, and connected in any mechanical way so as to drive the magneto, or the arrangement described leaves a space 13 within the main casing 14, and the magneto can be mounted in this space and on the shaft 11, if desired. I have not shown the magneto and its connections, because they have nothing to do with the real invention.

For convenience in constructing and assembling I arrange the casing in several parts, to wit, the part 14, which carries the cylinders 15, the part or sections 16, which carries the crank casing or compression chamber hereinafter referred to, and the part 17, which forms one end of the main casing. These several parts are secured together by bolts 18 and 19, as shown in Figs. 2 and 3, but obviously the parts may be separated along different lines and differently connected if desired, without affecting the real invention.

The casing comprising the aforesaid united parts turns on ball bearings 20, 21 and 22, as shown best in Fig. 1, though other suitable easy bearings can be provided. One end of the casing 14 is rigidly secured to a central plug or support 14^a which turns on the ball bearing 20 and which also rotates around a plug or block 24 which is fast to the shaft 11, and which carries the spark plug 25 which can be of any suitable or preferred construction. The spark plug 25 has its sparking points open to the port 26 (see Figs. 1 and 3) and this port connects

with the channels 27 and with the ports 27^a in the casing 14, the port 27^a communicating with the cylinders 15 as shown clearly in Fig. 3. Thus a spark will simultaneously 5 explode the gases in two opposed cylinders 15, and these will both be in registry with the channels 27 at the same time, as the drawing shows. The block 24 is also provided with exhaust channels 28 connecting 10 with the exhaust ports 29 near the ends of the cylinders 15, as shown in Fig. 1, and it will be seen that no exhaust valves are necessary, because the ports 29 will register with the channels 28 after an explosion, and 15 when the pistons are in the position shown in Fig. 1, while the continued rotation of the casing 14 will bring the ports and channels out of registry.

The engine is provided with intake channels 30 near one end of the machine, which 20 are in the part 17 of the main casing, and communicate with the crank casing or compression chamber 37 hereinafter referred to, and also at the proper moment register with 25 the channels 31 which receive the explosive gases from a pipe 32 leading from the carburetor, or other source of supply. These channels 31 are made in the block 33 which is stationary and can be conveniently held 30 rigid in a bracket 34 which is attached to the base of the engine. The block 33 has a suitable bearing 35 for the shaft 12, and the shaft also turns in a suitable bearing 36 in the engine frame 10. The inner end of 35 the shaft 12 is flanged as at 12^a, and connected to the part 17 of the casing, and has a ball bearing connection 36^a with the stationary shaft 11.

The channels 30 for the intake of the explosive mixture, connect with the compression chamber or crank casings 37 as above described and as shown in Fig. 1, and it will be observed that the channels 30 are in the rotatable part 17 of the casing, while the 45 channels 31 are in the stationary part 34 of the engine, so that no intake valves are required, as the rotation of the parts 17 hereinafter described, will open and close the intake ports at the proper times.

50 Each cylinder 15 of the engine is provided with a piston 38 which reciprocates in the cylinder, and which is suitably connected with its crank shaft. This connection may be in any usual or preferred way, and I 55 have shown the piston provided with a pin 39 on which the piston rod or pitman 40 is journaled and the outer end of the pitman 40 connects with the crank 42 of the crank shaft 43, this being mounted in suitable 60 bearings 44 which are preferably ball bearings, while the thrust of the shaft is provided for by a bearing 45 held in place by the removable nut or plug 46. The inner end of each crank shaft 43 is provided with 65 a bevel pinion 47 meshing with the station-

ary bevel gear 48 which is securely fixed to the shaft 11. It will thus be observed that when the crank shafts are rotated by the movement of the pistons 38, the tendency will be for the pinions 47 to turn the gear 48, but as this is fixed and cannot turn, the result will be that the movement will be imparted to the casing 14—16—17, which will rotate around the shaft 11 and on the bearings 20, 21 and 22.

70 To provide against any endwise movement of the casing, a bearing 49 is arranged behind the fixed gear 48, and between it and a part of the casing 16.

To provide for admitting the explosive 80 mixture from the chamber 37 to the front of the piston 38, the latter is provided with a port 50 which extends from one side through the inner piston end, as shown clearly in Fig. 5, and this registers with a channel 51 85 through the cylinder casing and connecting with the chamber 37.

The action of the engine is as follows: Assuming that an explosion has taken place 90 and that the pistons of opposed cylinders are in the position shown in Fig. 1. The channels 30 and 31 will be in registry and the explosive mixture will be admitted to the compression chamber 37. The bevel pinions 30 and 48 are as two to one, and consequently the continued rotation of the casing 14—16—17 will cause the pistons 38 to have a complete stroke before another explosion, and this will cut off the connection between the channels 30 and 31, and will compress 100 the gases already admitted to the chamber 37, and while the piston is in the position shown in Fig. 5, the fresh gases will momentarily flow through the channel 51 and port 50, thus forcing out the exploded gases, 105 and as the parts 50 and 51 are almost immediately out of registry, the continued movement of the piston 38 will further compress the gases in the cylinder, which will be exploded when the piston 38 is near the inner end of the cylinder. It will therefore be seen that the explosions will occur in opposed cylinders instantaneously, and that the continued rotation of the casing 110 will be brought about by the reciprocation of the pistons 38, while thorough provision is made for compression of the gases and for cutting off the intake and exhaust by the rotation of the engine casing itself.

115 It will also be noticed that the structure which I have described makes a very simple engine considering the number of its cylinders, and that it is of the two cycle type, and simpler and more efficient for this reason than many engines of this general kind.

120 I claim:—

1. An explosive engine comprising a stationary shaft, a rotatable shaft alining with the stationary shaft, a rotatable casing mounted on the stationary shaft and con- 125

- necting with the rotatable shaft, cylinders in the casing, said cylinders having their axes parallel with the axis of the aforesaid shafts, pistons reciprocating in the cylinders, means 5 for exploding charges in and exhausting them from the cylinders, and an operative connection between the pistons and the stationary support of the casing, by which the piston strokes are caused to rotate the casing.
- 10 2. An explosive engine comprising a stationary hollow shaft, a rotary hollow shaft mounted in a suitable support and receiving the end of the stationary shaft, stationary blocks at opposite ends of the machine, a 15 rotary casing revolving between the blocks, cylinders and pistons on the casing, the cylinders having intake ports communicating with ports in the block at one end of the machine, and exhaust ports communicating with ports in the block at the opposite end of the machine, crank casings on the main casing, crank shafts journaled in the several casings and operatively connected with their respective pistons, and a gear connection 20 between the crank shafts and a stationary abutment whereby the rotation of the crank shaft turns the main casing.
- 25 3. An explosive engine comprising a stationary shaft, a rotary shaft alining with the stationary shaft, stationary blocks at opposite ends of the engine, one of the blocks being provided with intake channels and the other with exhaust channels, a rotary casing supported on the aforesaid shafts and turning over the aforesaid blocks, said casing carrying a plurality of cylinders and gear casings, the gear casings having ports con-

necting with the intake channels, and the cylinders having ports connecting with the exhaust channels, suitable connecting ports 40 between the gear casings and the cylinders, pistons operating in the cylinders, crank shafts extending through the gear casings and operated by the cylinders, and a gear connection between the stationary shafts and 45 the several crank shafts by which the movement of the crank shafts turns the main casing.

4. An explosive engine comprising alining and unobstructive hollow shafts supporting the engine proper, one of said shafts being stationary and the other rotary, stationary blocks at opposite ends of the engine, one of said blocks having intake channels and the other of said blocks having exhaust 50 channels, a main casing rotating opposite the two blocks, said casing carrying a plurality of cylinders and gear casings, the gear casings being provided with ports to register with the intake channels, and the cylinders 55 with ports to register with the exhaust channels, spark plugs in one of the stationary blocks having connection with the cylinders, suitable ports leading from the gear casing to the cylinders, pistons in the cylinders, crank shafts connected with the cylinders and extending through the gearing casings, and a gear connection between the crank shafts and a stationary gear on the aforesaid 60 stationary shaft.
